(57) **CLAIM**

The ornamental design for a combination padded compression sleeve for shin and knee, as shown and described.

DESCRIPTION

FIG. 1 is a front perspective view of a combination padded compression sleeve for shin and knee, showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The equal-length broken lines in FIGS. 1, 2, 4 and 5 showing a logo depict portions of the combination padded compression sleeve for shin and knee that form no part of the claimed design.

The equal-length broken lines on the surface of the combination padded compression sleeve for shin and knee depict stitching that form part of the claimed design.

(Continued)

The equal-length broken lines in FIG. 1 showing a human leg depict environmental subject matter and form no part of the claimed design.
